CIGARETTE CASE.

No. 18,779.

Patented Dec. 4, 1888.

UNITED STATES PATENT OFFICE.

LE ROY W. FAIRCHILD, OF NEW YORK, N. Y.

DESIGN FOR A MATCH-BOX.

SPECIFICATION forming part of Design No. 18,780, dated December 4, 1888.

Application filed November 8, 1888. Serial No. 290,337. Term of patent 3½ years.

To all whom it may concern:

Be it known that I, LE ROY W. FAIRCHILD, of New York, in the county of New York and State of New York, have invented a new Design for Match-Boxes, of which the following is a specification.

This invention consists of a design for a match-box.

The accompanying photograph is a face view of a box having my design thereon.

The design in this case consists of a box having rounded ends, with an indentation at each of its two edges at or near the center of its length and having on its face the figure of a female, as shown in the accompanying photograph. The remaining portion of the surface, where not occupied by the figure of the woman, is covered with ornamental figures, mostly in a curved or scroll design, these with the figure of the female being struck up or otherwise formed in high relief, whereby a very rich and ornamental appearance is given.

I claim—

The design herein described and shown for a match-box.

In witness whereof I hereunto set my hand in the presence of two witnesses.

LE ROY W. FAIRCHILD.
